(57) **CLAIM**

The ornamental design for a hood for an automobile, as shown and described.

DESCRIPTION

FIG. 1 is a front elevational view of a hood for an automobile in accordance with our new design;

FIG. 2 is a top plan view of the hood in accordance with our new design of FIG. 1;

FIG. 3 is a left side elevational view of the hood in accordance with our new design of FIGS. 1 and 2;

FIG. 4 is a right side elevational view of the hood in accordance with our new design of FIGS. 1 to 3; and,

FIG. 5 is a front side perspective view of the hood for an automobile in accordance with our new design of FIGS. 1 to 4.

The appearance of the bottom of the hood as seen in FIGS. 1, 3, and 4 is for purpose of illustrating the boundaries of the exterior surface of the hood, and forms no part of the claimed design.

The broken lines portions of the hood form no part of the claimed design.
